(No Model.)

E. P. JOHNSTON.
CAR COUPLING.

No. 394,368.

Patented Dec. 11, 1888.

UNITED STATES PATENT OFFICE.

EDWARD P. JOHNSTON, OF WASHINGTON, DISTRICT OF COLUMBIA.

CAR-CO尤LING.

SPECIFICATION forming part of Letters Patent No. 394,368, dated December 11, 1888.

Application filed July 14, 1888. Serial No. 279,964. (No model.)

To all whom it may concern:

Be it known that I, EDWARD P. JOHNSTON, a citizen of the United States, residing at Washington, in the District of Columbia, have invented certain new and useful Improvements in Car-Couplers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to car-couplers of the link-and-pin type; and its object is to enable a tension to be put upon the pin when it is stuck or jammed in the draw-head, so that the cars will be uncoupled as soon as the pin is loosened, and whenever desired recoupled automatically. In making up or in distributing trains it frequently happens that a pin will become stuck so as to resist all efforts of the brakeman to withdraw it, owing to the crowding of the link by the adjoining car. Much time is lost by the brakeman being obliged to remain at that point until the strain on the pin has been relieved, so that he can uncouple the cars. By my device he can bring to bear upon the pin a tensile strain that will certainly withdraw it from the draw-head as soon as the retarding force is removed and insure the recoupling of the cars without further attention, thus allowing him to go on without unnecessary delay to other points where he is needed.

My invention consists of certain devices for the accomplishment of these purposes, as hereinafter described, and particularly pointed out in the claims.

In the accompanying drawings, Figure 1 is a side view showing the pin resting in the draw-head. Fig. 2 is an end view of the same. Fig. 3 is a side view showing the parts arranged to put a tension on the pin. Fig. 4 is a similar view showing the pin raised, and Fig. 5 is a plan view.

Similar letters refer to similar parts in all the figures.

A is the car-body, provided with the usual dead-blocks, B, and draw-bar C. On the end of the car are secured two parallel guide-rods,

D, on which slides a frame, E, composed of two parallel plates, e, provided with parallel slots e' and an upright bar, e², to which the plates e are attached. The guide-rods D pass through the slots e', which permit a movement of the frame E toward or away from the car-body in conformity with the similar movement of the draw-bar C under varying strains. The bar e² is U-shaped in cross-section, the open side 60 of the U being turned toward the car-body, as shown in Fig. 5.

The rod F is attached to the coupling-pin and passes loosely through holes in the outer ends of the plates e, and is provided with a collar, F', lying between the plates e e. Between the collar F' and the lower plate e is interposed a helical spring, G.

The collar F' has an arm, f, extending toward the bar e² and provided with a hole, 70 through which passes a rod, H, having a head at each end, as shown. The lower head is attached to the upper end of a helical spring, I, whose lower end is attached to a dog, K, pivoted on the bar e² at K' about midway of its 75 length. The back edge of the dog projects through a slot in the bar e², so as to be capable of engaging with a spring-pin, L, working in a socket, L', attached to the car-body at a point about midway of the guide-rods D. A 80 stop, k, limits the outward movement of the dog.

To the lower end of the rod F is secured a clamp, M, composed of two similar parts hollowed out to embrace the head of the coupling-pin and hold it firmly when closed upon it. The exterior of the clamp is conical, and a ring, m, drops down over it and holds the parts together when closed upon the pin, as shown.

The frame E is provided with some suitable device to raise it, and thereby lift the pin. This may consist of one or more levers, N, the inner end of which engages with the frame E at the point n, and which can be operated from the side of the car or from the top by means of the rod N'. Instead of levers, I may use cords or chains attached to the frame E and passing over pulleys to points convenient for operating them.

The mode of operation of these parts is as follows: Supposing the parts to be in the po-

sition in which they are shown in Fig. 1, and it is desired to lift the pin, the frame E is raised by depressing the lever N, the upward tension being communicated from the lower 5 plate e through the spring G to the collar F', rod F, clamp M, and so to the pin. If the pin is free to move, it will rise at once with the frame E; but if the pin is temporarily stuck the rod F will remain stationary and the upward movement of the frame E will compress the springs G and I, as shown in Fig. 3. The 10 spring I throws the dog K back into the U-shaped bar e², so that when it passes the pin L the dog will catch over the pin and prevent the frame E from dropping when the brakeman releases the lever N. The coupling-pin is thus subjected to the powerful tension of the spring G; and when relieved from its retarding force so as to be free to move the 15 20 coupling-pin will be immediately lifted by the spring G, and the parts will assume the position shown in Fig. 4. The arm f of the collar F' strikes the upper head of the rod H and pulls the dog K out of engagement with the pin L, so that the frame E is ready to drop back again to its original position. To prevent this and to hold the parts raised until the car is to be coupled again, a tubular follower, C', is introduced into the draw-head 25 30 35 40 45 50 55 60 65 70 75 80 85 90 95 100 105 110 115 120 125 130

It is evident that the details of construction of my device may be considerably altered without departing from the spirit of my invention.

Having thus described my invention, what I claim, and desire to secure by Letters Patent, is—

1. The combination, with the vertically-reciprocating coupling-pin, of a device, substantially as described, for lifting the same, and a yielding connection between said pin and said lifting device, which is adapted to receive the pressure applied to the lifting device and communicate the same to the coupling-pin, substantially as set forth.

2. The combination, with a vertically-reciprocating coupling-pin, of a lever, a vertically-movable frame connected with the lever, and a spring-connection between said frame and coupling-pin adapted to receive the pressure applied to the lever and communicate the same to the coupling-pin, substantially as described.

3. The combination, with a vertically-reciprocating coupling-pin, of a lever, a vertically-

movable frame connected with the lever, and a spring attached at its base to the said frame and secured at its top to the coupling-pin, substantially as set forth.

4. The combination, with a vertically-reciprocating coupling-pin, of a vertically-movable frame, a rod attached to the pin and passing through said frame, a spring interposed between said frame and a collar on the rod, and means for moving the frame, substantially as described.

5. The combination, with a vertically-reciprocating coupling-pin, of a vertically-movable frame, a rod attached to the pin and passing through the frame, a spring interposed between said frame and a collar on the rod, means for moving the frame, and a locking device to hold the frame in the raised position when the spring is compressed, substantially as described.

6. The combination, with a vertically-reciprocating coupling-pin, of a vertically-movable frame, a rod attached to the pin and passing through the frame, a spring interposed between said frame and a collar on the rod, means for moving the frame, a spring-actuated dog to lock the frame in its raised position when the spring is compressed, and yielding connections between the spring-dog and the rod, whereby the dog will be unlocked when the spring is released from compression and the rod rises, substantially as described.

7. The combination, with a vertically-reciprocating coupling-pin, of a device for lifting the same, a yielding connection between said pin and said lifting device adapted to receive the pressure applied to the lifting device and communicate the same to the coupling-pin, and a spring-actuated follower located in the draw-bar and adapted to support the pin when in its raised position, substantially as described.

8. The combination, with a draw-bar, of a tubular follower located within the same and provided with holes for the passage of the coupling-pin, and a spring arranged within the draw-bar behind the follower and adapted to force it normally outward, substantially as described.

9. The combination, with a vertically-reciprocating coupling-pin, of a lever, a vertically-movable frame connected with the lever, a spring attached at its base to the frame and rigidly secured at its top to the coupling-pin, and a spring-actuated follower located in the draw-bar and adapted to support the pin when in its raised position, as and for the purpose set forth.

10. The combination, with a vertically-reciprocating coupling-pin, of a lever, a movable frame connected with the lever, a clamp adapted to rigidly hold the coupling-pin, and a spring-connection between the clamp and the movable frame, as and for the purpose set forth.

11. The combination, with a vertically-reciprocating coupling-pin, of a lever, a vertically-movable frame connected with the lever, a rod passing through the frame, a spring-connection between the rod and the frame, a clamp secured to the rod and adapted to rigidly hold the coupling-pin, and a spring-actuated follower located in the draw-bar and

adapted to support the pin when in a raised position, substantially as set forth.

In testimony whereof I affix my signature in presence of two witnesses.

EDWARD P. JOHNSTON.
